CLAIM

The ornamental design for a panel rail saddle for solar module, as shown and described.

DESCRIPTION

FIG. 1 is a top perspective view of a panel rail saddle for solar module showing the new design in environmental use; FIG. 2 is a top perspective view of the panel rail saddle for solar module;

FIG. 3 is a bottom perspective view of the panel rail saddle for solar module of FIG. 2;

FIG. 4 is a top plan view of the panel rail saddle for solar module of FIG. 2;

FIG. 5 is a side elevational view of the panel rail saddle for solar module of FIG. 2;

FIG. 6 is a bottom plan view of the panel rail saddle for solar module of FIG. 2; and,

FIG. 7 is an enlarged rear view of the panel rail saddle for solar module of FIG. 2.

The broken lines shown represent environmental subject matter and form no part of the claimed design.
